ATTORNEY

UNITED STATES PATENT OFFICE.

CLARENCE VILAS KUESTER, OF MENASHA, WISCONSIN.

CASE WITH CLIP.

Application filed May 18, 1928. Serial No. 278,822.

My present invention has reference to a supporting clip for pencil cases or like cases, and my object is the provision of a device for this purpose which will not only serve as a supporting clip but which will effectively brace and reinforce the back of the case.

To the attainment of the above broadly stated objects the invention consists in the improvement as hereinafter described and definitely claimed.

In the drawings:

Figure 1 is a rear elevation of a pencil or like case equipped with the improvement.

Figure 2 is a sectional view approximately on the line 2—2 of Figure 1.

Figure 3 is a sectional view approximately on the line 3—3 of Figure 2.

Figure 4 is a view substantially similar to Figure 3 but illustrating a slight modification.

Figure 5 is a transverse sectional view approximately on the line 5—5 of Figure 1.

In the showing of the drawings, the improvement is disclosed in applied position on a leather or like fabric pencil or pen case 1. Obviously the improvement may be employed in connection with other types of cases.

Arranged on the inner face of the back of the case 1 there is an elongated metal plate 2. This plate is comparatively thin but is of sufficient strength to amply reinforce the back of the case, so that the bulging of the case will be effectively prevented. The metal plate 2, at desired points throughout its length is slotted both longitudinally and transversely and the metal bounded by these slits provide bendable ribs 3 designed to be first arranged rightangularly with respect to the case 1 and to be inserted through the back thereof and thereafter bent in hook-shape against the outer face of the back of the case, as disclosed by the drawings.

The plate 2 has its upper end tapered and merges into a tongue 4. This tongue is also bent at a right angle with respect to the plate 2 and is forced through the back of the case 1 and thereafter arched and extended longitudinally in a downward direction against the back of the case. The outer end of the tongue is rounded away from the case, as clearly disclosed by the drawings and the tongue provides the supporting clip for the case.

In Figure 4 the construction is similar to that just described except that the plate 5 is fluted or corrugated longitudinally to more effectively grip the back of the case when secured thereon, and the flutes or corrugations provide guides for the pencil or like instrument which is inserted in the case.

The simplicity of the construction will, it is thought be perfectly apparent to those skilled in the art without further detailed description.

Having described the invention, I claim:

The combination with a flexible case, of a plate arranged in the case and which plate is fluted longitudinally and of a length slightly less than the length of the case, said plate having integral bendable tongues which are passed through the back of the case and forced against such case, the outer end of the plate having its edges inclined toward the center thereof and the center formed with a reduced extension providing a tongue which is designed to be bent rightangularly with respect to the plate and to be passed through the back of the case and thereafter rounded downwardly and to contact with the case and from thence outwardly to form a clip for the case.

In testimony whereof I affix my signature.

CLARENCE VILAS KUESTER.
